(57) CLAIM

What is claimed is the ornamental design for a cosmetic palette, substantially as shown and described.

DESCRIPTION

FIG. 1 is a top, front and right side perspective view of a new design for a cosmetic palette shown in the closed position; FIG. 2 is a top, front and right side perspective view of the cosmetic palette shown in the open position;

FIG. 3 is a front elevation view of the cosmetic palette shown in FIG. 1;

FIG. 4 is a top plan view of the cosmetic palette shown in FIG. 1;

FIG. 5 is a rear elevation view of the cosmetic palette shown in FIG. 1;

FIG. 6 is a right side elevation view of the cosmetic palette shown in FIG. 1;

FIG. 7 is a left side elevation view of the cosmetic palette shown in FIG. 1; and,

FIG. 8 is a top, right side perspective view of the cosmetic palette shown in FIG. 1, showing a drawer in an extended position.

The broken lines shown in the figures are for illustrative purposes only and form no part of the claimed design.
